CLAIM

The ornamental design for a lid, as shown and described.

DESCRIPTION

FIG. 1 is a top perspective view of a lid showing a new design;

FIG. 2 is bottom perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken lines show portions of the design that form no part of the claimed design.

1 Claim, 5 Drawing Sheets
